UNITED STATES PATENT OFFICE

125,487

DESIGN FOR A RADIO TRANSMITTER

Frederick H. Drake, Boonton, and Atherton Noyes,
Jr., Mountain Lakes, N. J., assignors to Aircraft
Radio Corporation, Boonton, N. J., a corpora-
tion of New Jersey

Application December 5, 1940, Serial No. 97,101

Term of patent 14 years

To all whom it may concern:

Be it known that we, Frederick H. Drake and Atherton Noyes, Jr., citizens of the United States, residing at Boonton, county of Morris, State of New Jersey, and Mountain Lakes, county of Morris, State of New Jersey, have invented a new, original and ornamental Design for a Radio Transmitter, of which the following is a specification, reference being had to the accompanying drawing, forming part hereof, and wherein:

Fig. 1 is a perspective view of the radio trans-

mitter, showing our new design, as seen when looking downwardly towards the front and one side of the radio transmitter; and

Fig. 2 is a similar perspective view of the radio transmitter as seen when looking downwardly upon the back and the other side of the same.

We claim:

The ornamental design for a radio transmitter, as shown.

FREDERICK H. DRAKE.
ATHERTON NOYES, JR.
